UNITED STATES PATENT OFFICE.

WALTER RODECK, OF NEW DURHAM, NEW JERSEY.

CLIP.

1,153,135.

Specification of Letters Patent.

Patented Sept. 7, 1915.

Application filed January 16, 1915. Serial No. 2,690.

To all whom it may concern:

Be it known that I, WALTER RODECK, a citizen of the United States, and a resident of New Durham, in the county of Hudson and State of New Jersey, have invented a new and Improved Clip, of which the following is a full, clear, and exact description.

The object of the invention is to provide a new and improved clip for use on pockets of overalls, coats, vests and other garments, and more especially designed for holding an ordinary two-foot carpenter's rule securely in position and for allowing ready withdrawal of the rule whenever it is desired to 15 use the same.

Another object of the invention is to permit the use of the clip in conjunction with the rule as a scratch gage.

In order to accomplish the desired result, 20 use is made of a casing for the passage of a two-foot rule or similar instrument, the casing having a flaring mouth for the convenient entrance of the rule, a side of the flaring mouth serving as an abutment when 25 using the casing with the rule therein as a scratch gage, the casing having spring tongues at the sides adapted to bear against the sides of the rule and the front of the casing having a spring arm adapted to bear 30 against the outside of the pocket to which the clip is applied.

A practical embodiment of the invention is represented in the accompanying drawings forming a part of this specification, in 35 which similar characters of reference indicate corresponding parts in all the views.

Figure 1 is a front elevation of the clip; Fig. 2 is a rear elevation of the same as applied to an ordinary two-foot folding rule; 40 Fig. 3 is a cross section of the clip on the line 3—3 of Fig. 1; Fig. 4 is a sectional plan view of the clip as applied to a rule, the section being on the line 4—4 of Fig. 2; Fig. 5 is a reduced front elevation of the clip as applied to a pocket for holding a rule; and 45 Fig. 6 is an edge view of the clip as applied to a rule and showing the same in position for use as a scratch gage, the two being shown in section.

50 A casing A of approximately rectangular shape and open at the back is provided with a flaring mouth B for the convenient insertion of an ordinary two-foot carpenter's rule C or a similar instrument to be held in position by the clip. One of the sides of the mouth B forms an abutment when using the

clip in conjunction with the rule C as a scratch gage (see Fig. 6), the side of the mouth then abutting against the edge of the work D with the point of a pencil E resting on the inner end of the rule C, to make a mark on the face of the work D, as will be readily understood by reference to Fig. 6.

The front of the casing A is provided with a depending arm F and a spring is struck up from the front of the casing A and the said arm F, and the free end of the tongue G is provided with an inwardly extending knob G' adapted to bear lightly on the face of the rule C when using the latter in conjunction with the clip as a scratch gage (see Fig. 6). The sides of the casing A are provided with depending arms H and spring tongues I are struck up from the sides of the casing A and the arms H, and the said spring tongues I are curved inwardly near their free ends so as to bear against the sides of rule C to securely hold the latter in position in the casing A. When it is desired to use the clip for holding the rule C in the 80 pocket J of an overall, coat, vest or other similar garment K, then the casing A is passed into the pocket with the tongue G on the outside of the pocket so that the knob G' bears on the outer surface of the pocket to 85 securely hold the clip in position in the pocket. It will be noticed that the base of the spring tongue G is close to the mouth B of the casing A so that when the clip is in 90 position in the pocket only the mouth B projects on the top of the pocket, so that the user can readily see the mouth when placing the rule C in position in the casing. When the rule C is in position in the clip at the time the latter is attached to the pocket J 95 then the spring tongues I bear with sufficient force against the sides of the rule C to prevent the latter from being displaced on the user bending over or otherwise moving the body. The casing A is preferably open at the back, as plainly indicated in Figs. 2, 3 and 4, so that the casing is not liable to bind hard on the rule C to allow convenient insertion and removal of the rule and without danger of unduly scratching the graduated faces of the rule.

The clip is very simple and durable in construction and can be readily applied to a pocket for holding a rule, or it can be used in conjunction with the rule to form a scratch gage, as above described and shown in Fig. 6.

Having thus described my invention, I claim as new and desire to secure by Letters Patent:

1. A clip for holding an ordinary rule or like instrument, comprising a casing open at the back and provided with a flaring mouth for the ready introduction of an instrument, the casing having depending front and side arms, a front spring tongue struck up from the front of the casing and its front arm, and having its terminal extending inward beyond the inner face of the front, and side spring tongues struck up from the sides of the casing and the side arms, the said side 10 spring tongues being curved inward near their terminals.
2. A clip for holding an ordinary rule or like instrument, comprising a casing having

a flaring mouth for the convenient insertion of the rule in the casing, side spring tongues on the sides of the casing and adapted to bear against the sides of the rule, and a front spring tongue on the front of the casing and adapted to bear against the face of the rule or against the face of a pocket to support the rule within the pocket, the base of the said spring tongue being adjacent the said flaring mouth to hold the latter above the top of the pocket.

In testimony whereof I have signed my name to this specification in the presence of two subscribing witnesses.

WALTER RODECK.
